CLAIM

The ornamental design for a pedestal-mounted coil for holding a hair dryer, as shown and described.

DESCRIPTION

FIG. 1 is an environmental perspective view of a coil for holding a hair drier showing my new design;

FIG. 2 is a perspective view of a coil for holding a hair drier;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear elevational view thereof; and,

FIG. 8 is a bottom plan view thereof.

The broken lines in the drawings are included for the purpose of illustration and form no part of the claimed design.
